UNITED STATES PATENT OFFICE.

HARRY E. TOWNSEND, OF BROOKLYN, NEW YORK.

ASSEMBLING MACHINE.

Application filed December 9, 1925. Serial No. 74,295.

My invention relates to machines for handling articles, and has special reference to machines of this character that are particularly adapted for use in assembling articles, such as hard candies, in stacks or rolls.

One object of the invention is to provide a machine of this character which is simple in construction and rapid and efficient in operation, and which is particularly adapted 10 for use in handling hard candies that are coated with sugar and thus are liable to become more or less moist and sticky in warm weather, and are more or less ununiform in shape and size.

Another object of the invention is to provide a machine of the character indicated in which there is provision of means for eliminating broken pieces, so as to ensure 15 that no such pieces shall reach the assembled articles.

The several features of the invention whereby the above mentioned and other objects may be attained, will be clearly understood from the following description and 20 accompanying drawings, in which:

Figure 1 is a longitudinal sectional view of a machine embodying the features of the invention in their preferred form;

Fig. 2 is a view corresponding to a portion of Fig. 1 on an enlarged scale and showing certain parts of the machine in a different position;

Fig. 3 is a side elevation, on an enlarged scale, of the rear portion of the machine;

Fig. 4 is a detail sectional view taken on the line 4—4 of Fig. 5;

Fig. 5 is a transverse sectional view taken on the line 5—5 of Fig. 3;

Fig. 6 is a transverse sectional view taken on the line 6—6 of Fig. 3;

Fig. 7 is a sectional view, on an enlarged scale, taken on the line 7—7 of Fig. 1;

Fig. 8 is a detail sectional view taken on the line 8—8 of Fig. 1; and

Fig. 9 is a plan view partly broken away 45 looking face down on the inclined raceways of the machine.

The machine illustrated in the drawings is particularly adapted for use in assembling 50 articles, such as hard candies that are in the form of circular disks, in stacks or rolls. As shown, the machine in general comprises a hopper 2 for receiving the articles; agitating devices 4 which selectively arrange the 55 articles in rows with the articles in each row arranged edge to edge in upright posi-

tion; an endless conveyor 6 which receives the articles as thus arranged from the agitating devices and hopper; raceways 8 to which the several rows of articles are delivered by said conveyor, and which are inclined 60 downwardly and diverge toward their lower ends; and devices for causing the endmost articles in the several raceways to be successively delivered into position to permit 65 them to be easily removed either by hand or machine, the articles thus delivered being arranged side by side.

The hopper 2 is provided with longitudinal side walls 12 and front and rear end walls 14.

The bottom of the hopper comprises a plurality of bars 16 having their ends secured to the front and rear walls 14 and being arranged side by side and spaced apart a distance slightly greater than the thickness of the articles.

The agitating devices 4 comprise bars or rods of wood which are arranged to slide upon the bottom bars 16 and have their ends projecting through guiding apertures in the front and rear walls 14 of the hopper.

The agitating devices or rods 4 are rectangular in cross-section except that the upper portions of their sides extending between the front and rear walls 14 are beveled or inclined upwardly 70 and outwardly as indicated at 18, the lower portions of the sides of said rods 4 being substantially flush with the sides of the bottom bars 16.

These agitating devices or rods 4 are reciprocated in opposite directions alternately which causes the articles to work down over the inclined sides of the bottom bars 16, the articles entering each space 75 between the bars in upright position and arranged one behind the other.

The endless conveyor 6 is positioned beneath and in close proximity to the spacing bars 16 so that when the articles are received in the spaces between the bars they 80 rest upon the conveyor.

The front end of the conveyor is spaced a distance back of the inner lower edge of the front wall of the hopper, and the conveyor is operated to carry the articles forwardly thereon and discharge 85 them through said space, the upper ends of the raceways 8 being arranged so as to receive the articles as they pass through said discharge space or opening.

The endless conveyor 6 is driven back and forth alternately, the advancing movements thereof being substantially twice as long as its back- 90

100

105

110

115

ward movements. Such actuation of the conveyor causes the articles to be fed toward the raceways and at the same time prevents them from materially piling up and clogging the discharge space or opening adjacent the inlet ends of the raceways. To still further prevent the articles from piling up and clogging said discharge space or opening, a device is provided which comprises a transverse plate 20 arranged adjacent the upper portion of the inner side of the front wall of the hopper and having its upper end secured to arms 22 depending from a rock shaft 24 which is journalled in suitable bearings in brackets 26 mounted on the upper edges of the longitudinal sides of the hopper. The plate 20 has depending teeth 28 secured to its lower end and extending downwardly through the spaces between the agitating devices 4 and between the bottom or spacing bars 16. Upon actuation of the rock shaft 24 the plate 20 and the teeth 28 are carried back and forth toward and from the front wall 14, and thus tend to work the articles back from the front wall and away from said discharge opening, the lower end of the teeth 28 being spaced a sufficient distance from the front end of the conveyor 6 to permit the articles to pass one at a time beneath each of them.

The agitating devices 4 are reciprocated in opposite directions alternately, as above described, by means of rocker arms 30 and 32 which are alternately arranged. The lower ends of the arms 30 and 32 are mounted upon a rock shaft 34 and their upper ends are forked so as to embrace rearwardly extending rods or pins 36 secured to the rear ends of the agitating devices 4 and each is positioned between abutment washers and nuts 38 screw-threaded upon the pins. The oscillating arms 32 are secured to the rock shaft 34 so as to be actuated thereby, while the arms 30 are pivotally mounted upon the rock shaft 34 and means is provided for oscillating the latter arms upon the rock shaft. The rock shaft 34 has its ends extended through bearings in rearwardly projecting brackets 42 and is actuated by a shaft 40 having its ends extending through and journalled in bearings in said brackets 42. The ends of the shaft 40 project beyond the outer sides of the brackets 42 and are reduced in diameter and arranged eccentrically of the axis of the shaft. The connection between the shaft 40 and the rock shaft 34 comprises links 44 having one end pivotally mounted upon the eccentric ends of the shaft 40 and having their other ends pivotally connected by studs or pins 46 with the free ends of arms 48 that are secured to the projecting ends of the rock shaft 34.

The rocker arms 30 form one arm of bell crank levers, the other arms 50 of which engage a rod 52, the two endmost arms 50 being

provided with apertures through which the rod loosely extends so as to support the rod, and the remaining arms 50 having bifurcated ends that straddle the rod. The ends of the rod 52 extend through clearance openings in the brackets 42, and links 54 connect the ends of said rod with the eccentric ends of the actuating shaft 40. With this construction, it will be apparent that upon rotation of the shaft 40, the rocker arms 30 and 32 will be reciprocated in opposite directions as desired.

The shaft 40 is driven from the driving shaft 58 of the machine through gears 60 and 61 (Fig. 4) secured to the shaft 40 and to a shaft 62 having its ends journalled in bearings in the brackets 42. The shaft 62 carries a spiral gear 64 that engages a spiral gear 66 mounted upon the rear end of a downwardly and forwardly inclined shaft 68 which has its rear end journalled in a bearing on a bracket 69 secured to the right hand bracket 42 and having its forward end journalled in a bearing on the machine frame. The lower end of the inclined shaft 68 carries a spiral gear 72 that is engaged by a spiral gear 74 carried by a transverse shaft 76 that has its ends journalled in suitable bearings in the frame of the machine, and is driven by a sprocket chain 78 that passes over sprocket wheels 80 secured on said shaft and a shaft 82. This shaft 82 is driven through a large gear 84 secured thereon and engaged by a pinion 86 carried by the driving shaft 58, the latter shaft being continuously driven by a pulley 87.

The endless conveyor 6 passes over pulleys or drums 88 that are carried by shafts 89 and 90, respectively, journalled in bearings in the machine frame. The upper run of the conveyor passes over a supporting table 91 so as to maintain it substantially flat. The conveyor may be divided longitudinally into a number of sections, which are maintained under proper tension by upwardly sprung 110 pressed tension rolls 92 that engage the lower runs thereof. One end of the drum shaft 89 carries ratchet wheels 93 and 94 having their teeth oppositely arranged and engaged by actuating pawls 95 and 96. These pawls 95 and 96 are pivotally mounted on an oscillating lever 97 which is pivotally mounted upon the outer end of the drum shaft 89. The pawls are pressed toward the ratchet wheels by a spring 98 coiled about a stud 99 on the lever 97, and has its ends engaging the top sides of the pawls. The pawl 96 is adapted to ride upon a pin 100 projecting from the side of the hopper during a portion of the movement of the lever 97 in both directions. With this construction, during the movement of the lever 97 in a counter clockwise direction, viewing Fig. 3, the pawl 95 and ratchet wheel 93 act through the shaft 89 to rotate the conveyor 6 in a 120 125 130

direction to carry the articles toward the raceways 8; and during the movement of the lever 97 in the opposite direction, the pawl 96 and ratchet wheel 94 act to reverse the 5 movement of the conveyor. During the latter movement of the lever 97, the pawl 96 rides upon the pin 100 and thereby is not permitted to operatively engage its ratchet wheel until near the last half of said movement of the lever 97. Thus it will be apparent, that upon actuation of the oscillating lever 97, the endless conveyor 6 will be driven in opposite directions, the advancing movements thereof being substantially twice 10 as long as its retracting movements, as above described. The lever 97 is actuated by a link or rod 101 having one end pivotally connected with the lever and its other end pivotally connected with a crank arm 102 secured on 15 one end of the shaft 62.

The rock shaft 24 that carries the oscillating device or comb 28 is actuated by a link or rod 103 having one end pivotally connected with an arm 104 secured to said shaft, 20 and having its other end pivotally mounted on the reduced end 105 of the shaft 62, which end is arranged eccentrically to the axis of the shaft.

The major upper portions of the raceways 30 8 are arranged side by side and spaced apart, and each comprises a bottom strip 106, and a top strip 107 which is provided with a longitudinally extending groove for receiving and guiding the upper portions of the 35 articles as they ride down upon the bottom plate. The top plates 107 are all secured to the under side of transverse bars 108 having their ends secured on the upper ends of standards 109 secured to the machine frame. 40 The bottom strips 106 are all mounted upon transverse bars 110 secured to the standards. Screw bolts 111 extend loosely through apertures in the cross bars 110 and are screw-threaded into the under sides of the bottom strips 106 so as to hold the strips from longitudinal movement but permitting limited vibratory movement thereof. The top surface of the upper portion 112 of each of the bottom strips 106 is substantially flat, while 45 the remaining portion thereof is provided with a longitudinal groove 113. With this construction, in case a broken article enters one of the raceways, the vibration of the plate by means hereinafter described, causes 50 it to be discharged over the edge of the flattened portion 112 of the strip, and thus it is prevented from riding down the length of the raceway.

The several bottom strips 106 of the raceways are vibrated by means of devices comprising adjustable screws 114 which are mounted upon a plate 115 that is secured on the upwardly turned end of a lever 116 which is pivotally mounted upon the 55 sprocket wheel shaft 82. The lever 116 car-

ries a cam roll 117 that is held in engagement with a cam 118 on the sprocket wheel shaft 76 by means of a coil spring 119 having one end connected with the lever and its other end secured to the machine frame. With 70 this construction, an oscillating movement is imparted to the cam lever 116 which causes the ends of the screws 114 to strike against the under sides of the bottom strips of the raceways and thus vibrate the strips. 75

The remaining portions of the raceways 8, comprise bottom members 120 each of which is provided with a relatively deep longitudinally extending groove 121 for guiding the articles, and all of the members are secured upon a sheet metal plate 122 which has its upper end mounted upon a transverse bar 124 that is supported and extends between standards 126 secured to the machine frame. The lower portion of the plate 122 is mounted upon a transverse bracket member 128 secured to the frame. Bolts 130 extend through apertures in the transverse supporting bar 124 and bracket member 128 and are screw-threaded into the sheet metal plate 122 so as to hold the plate from longitudinal movement but permitting it to be vibrated so as to vibrate the raceway members 120. Top strips 132 extend over the members 120, and have their upper ends secured by bolts 134 to a transverse bar 136 extending between the standards 126, and have their lower portions secured by bolts 138 to a transverse bar 140 extending between standards 142 which is secured to the bracket member 128. The lower ends of the strips 132 are spaced a distance back of the forward ends of the bottom raceway members 120. The sheet metal plate 122 and the bottom members 120 of the raceways are 90 adapted to be vibrated by means of a hammer 144 which is formed upon the upwardly turned end of a lever 146 which is pivotally mounted upon the rear sprocket wheel shaft 76 and is provided with a cam roll 148 which is held in engagement with a cam 150 on the lower sprocket wheel shaft 82 by means of a coiled spring 152 having one end connected with the lever and its other end secured to the machine frame. 100

An escapement bar 153 extends transversely over the lower end portions of the raceways in front of the lower ends of the top strips 132 and is provided with depending ears on its ends that are secured on pivot shafts 154 and 155 which extend through bearings 156 mounted upon the bracket member 128, the pivot shafts being in alinement and having their axis in substantially the same plane with the axes of the articles as they move down the raceways. The under side of the bar 153 is curved concentrically with the axis of the bar, and its radius of curvature is slightly greater than that of the articles. When the 115 120 125 130 135 140 145 150 155 160

- escapement bar 153 is in the position shown in Fig. 1, it serves as a stop to limit the downward movement of the candies in the several raceways and causes the candies to be uniformly arranged in each raceway one behind the other and in contact with each other, and with the candies in the several raceways arranged side by side, and with the endmost candies in close proximity.
- 10 When the escapement bar is turned in a counter-clockwise direction to the position shown in Fig. 2, it permits the articles to advance down the raceways until the endmost articles engage the under curved surface of
- 15 the bar, which limits said advancing movement of the roll. When the escapement bar 153 is then swung back to its initial position, it releases said endmost row of articles and engages the next succeeding row so as
- 20 to hold it from advancing movement, but permits the row that is released to drop down into engagement with a second stop member 158. A supporting plate 159 is interposed between the ends of the raceways
- 25 and the stop member 158. The stop member 158 comprises a plate or bar having upwardly extending ears 160 on its ends which embrace and are secured to a shaft 162 having its ends pivotally mounted in brackets
- 30 164 secured on the bracket member 128. The members 153 and 158 are connected to move in unison so that when the member 153 releases the endmost row of articles to permit it to separate from the others, the
- 35 stop members 158 is brought into position to limit said movement of that row, and when the member 153 is swung in the opposite direction to permit limited advancing movement of the articles in the several race-
- 40 ways, as above described, the stop member 158 is swung forwardly out of the way so as to permit the row of articles that may be held thereby to drop down into a discharge chute 166. It is intended, however,
- 45 that the separated row of articles shall be removed before the stop member 158 is swung out of the way. In case, however, the operator should find that there is not the requisite number of articles in the row
- 50 or for other reasons, he may permit the row to remain in position and thus be discharged through the discharge chute 166 when the stop member 158 is released. Because of the thickness of the walls between the race-
- 55 ways, the articles delivered therefrom to the station adjacent the stop 158 are spaced apart, but it will be apparent that in removing the row the articles may be easily brought together to form a stack or roll.
- 60 It will be apparent that the members 153 and 158 may be operated either by hand or automatically. In the construction illustrated in the drawings they are shown as operable by means of a hand operated lever
- 65 168 that is secured upon a shaft 170 and is

pressed upwardly by means of a coiled spring 180 having one end secured to an arm that is secured to the shaft 170 and having its other end secured to the machine frame. The escapement member 153 is connected with the lever 168 through an arm 182 (Fig. 9) secured to the projecting end of the pivot shaft 154 and connected by a link 184 with the free end of the lever. The stop member 158 is connected with the lever 168 by an arm 186 secured to the projecting end of the shaft 162 and connected by a link 188 with the free end of the lever 168. The lever 168 is provided with an operating handle 190.

In the position of the parts shown in Fig. 1, the lever 168 is pressed downwardly by the operator so as to move the stop member 158 into its stopping position to be engaged by the row of articles discharged from the raceways, and the member 153 into engagement with the lowermost articles in the several raceways. When the handle 190 is released by the operator, the lever 168 is swung upwardly by its spring to position the members 153 and 158 in the position shown in Fig. 2, as above described.

The forward edge of the escapement 153 is spaced a sufficient distance above the bottom plate 120 so that in case a broken or small piece of candy reaches the lower end of its raceway it may pass beneath the escapement and be discharged into the chute 166, whereupon the next candy in the raceway may move downwardly by gravity to take its place against the escapement.

As will be evident to those skilled in the art, my invention permits various modifications without departing from the spirit thereof or the scope of the appended claims.

What I claim is:

1. A machine for handling articles of the kind described having, in combination, a hopper having a discharge opening adjacent to its lower end, an endless conveyor adjacent to the bottom of the hopper for conveying the articles toward said discharge opening, means for arranging the articles on said conveyor in rows extending longitudinally thereof, with the articles in each row arranged edge to edge in upright position, and means for imparting advancing and retracting movements to said conveyor to tend to move the articles toward and from said discharge opening, said advancing movements being of greater extent than the retracting movements.

2. A machine for handling articles of the kind described having, in combination, a hopper, an endless conveyor adjacent to the bottom of the hopper having one end thereof spaced a distance away from the lower end of a wall of said hopper to provide an opening through which the articles may be discharged, means for arranging the articles on said conveyor in rows extending longitudi-

nally thereof with the articles in each row arranged edge to edge in upright position, and means for imparting advancing and retracting movements to said conveyor to tend 5 to move the articles toward and from said discharge opening, said advancing movements being of greater extent than the retracting movements.

3. A machine for handling articles of the kind described having, in combination, a hoppper, a plurality of bars arranged longitudinally adjacent to the bottom of the hopper and spaced apart a distance slightly greater than the thickness of the articles so 10 as to permit the articles to be positioned between them in upright position, means for thus positioning the articles between the bars, means for reciprocating alternate bars in opposite directions, and a conveyor extending beneath said bars for conveying the 15 articles longitudinally of the bars and discharging them adjacent to one end thereof.

4. A machine for handling articles of the kind described having, in combination, a hopper, a plurality of bars arranged longitudinally adjacent to the bottom of the hopper and spaced apart a distance slightly greater than the thickness of the articles so 20 as to permit the articles to be placed in upright position between the bars, agitating members mounted to slide longitudinally over the tops of the bars, said members being spaced apart so as to permit the articles to drop 25 downwardly between the bars, means for reciprocating said agitators longitudinally, and a conveyor for conveying the articles thus positioned between the bars longitudinally thereof and discharging them adjacent to one end thereof.

40 5. A machine for handling articles of the kind described having, in combination, a hopper, a plurality of agitating members arranged longitudinally of the hopper and adapted to be reciprocated longitudinally, the lower portions of said members being spaced apart a distance slightly greater than the thickness of said articles, and the upper portions thereof being inclined outwardly so as to direct the articles in upright position 45 downwardly between said members, means for reciprocating said members, and means for conveying the articles in the position arranged by said members from said hopper.

55 6. A machine for handling articles of the kind described having, in combination, a hopper, a plurality of agitating members arranged longitudinally adjacent the bottom of the hopper and spaced apart a distance 60 slightly greater than the thickness of the articles, means for reciprocating alternate agitators in opposite directions, and means for conveying the articles from said hopper after they pass between said agitating members.

7. A machine for handling articles of the kind described having, in combination, a hopper having a discharge opening adjacent to its lower end, a plurality of bars arranged longitudinally adjacent to the bottom of the hopper and spaced apart a distance slightly greater than the thickness of the articles, means for directing the articles downwardly between the bars comprising agitating members mounted to slide longitudinally over 70 the top longitudinal sides of said bars, means for reciprocating said agitating members longitudinally, an agitator arranged adjacent the discharge end of said bars and agitating members and having teeth extending 75 downwardly between said agitating members and between said bars, and means for oscillating said agitator to cause the teeth thereof to work back and forth in said spaces.

8. A machine for handling articles of the kind described having, in combination, means for assembling the articles in rows with the articles in each row arranged edge to edge in upright position, raceways for 90 receiving the several rows, respectively, and having their forward portions spaced apart, each of said raceways being inclined downwardly from said assembling means and having its forward portion comprising a flat 95 strip upon which the articles rest, and a grooved strip for guiding the upper portions of the articles.

9. A machine for handling articles of the kind described having, in combination, 100 means for assembling the articles in rows with the articles in each row arranged edge to edge in upright position, raceways for receiving the several rows, respectively, each of said raceways being inclined downwardly 105 from said assembling means and the upper portions thereof being substantially parallel, and the remaining portions diverging so as to position their rear or lower ends in close proximity, each raceway comprising a bottom strip upon which the articles rest, and a grooved strip for guiding the upper portions of the articles, the upper end portions of said bottom strips being spaced apart and substantially flat.

110 10. A machine for handling articles of the kind described having, in combination, means for assembling the articles in rows with the articles in each row arranged edge to edge in upright position, raceways for 115 receiving the several rows, respectively, inclined downwardly from said assembling means, and each comprising a strip upon which the articles rest, and a grooved strip for guiding the upper portions of the articles, said bottom strip being loosely mounted, and means for vibrating said bottom strip.

11. A machine for handling articles of the kind described having, in combination, a plurality of raceways arranged side by side 120

70

80

and inclined downwardly and rearwardly, the lower end portion of said raceways comprising a plate and a plurality of strips arranged side by side and spaced apart 5 mounted upon the plate for receiving the articles between them, said plate being loosely mounted, and means for vibrating said plate.

12. A machine for handling articles of 10 the kind described having, in combination, means for assembling the articles in rows arranged side by side with the articles in each row arranged side by side, a device pivotally mounted with its axis substantially 15 in the plane of the axes of the articles of said rows engaging the endmost row to hold the several rows from advancing movement and adapted to be released from said endmost row to permit the several rows to ad- 20 vance and to re-engage the endmost row to limit said advancing movement thereof, and adapted to be thereafter released from said endmost row and by engagement with the next succeeding row to hold the remaining 25 rows from advancing movement, and means for thus operating said device.

13. A machine for handling articles of the kind described having, in combination, means for assembling the articles in rows 30 arranged side by side with the articles in each row arranged side by side, a device engaging the endmost row to hold the several rows from advancing movement and adapted to be released from said endmost row to 35 permit the several rows to advance and to re-engage the endmost row to limit said advancing movement thereof, and adapted to be thereafter released from said endmost row and by engagement with the next suc- 40 ceeding row to hold the remaining rows from advancing movement, means for thus operating said device, a stop for limiting the last-mentioned advancing movement of said endmost row, and means for releasing 45 said stop.

14. A machine for handling articles of the kind described having, in combination, means for assembling the articles in rows arranged side by side with the articles in 50 each row arranged side by side, a member pivotally mounted with its axis substantially in the plane of the axes of said rows, and having a pocket adapted when the member is in one position to receive the endmost row 55 to hold the rows from advancing movement, when moved to another position to release said endmost row and to engage the next succeeding row to hold the remaining rows from advancing movement, and means for 60 operating said member.

15. A machine for handling articles of the kind described having, in combination, means for assembling the articles in rows arranged side by side with the articles in

each row arranged side by side, a device 65 adapted to be operated to engage the endmost row to hold the several rows from advancing movement, to release the endmost row to permit the several rows to advance a predetermined distance, to re-engage said 70 endmost row to hold the rows from further advancing movement, to release the endmost row and to engage the next succeeding row to hold the remaining rows from advancing movement, a stop for limiting the advancing movement of said first-mentioned endmost row when released from said device, and means for simultaneously releasing said stop from said last-mentioned row and for 75 releasing said device from said next succeeding row and for causing said reengagement of said device with said last-mentioned row.

16. A machine for handling articles of the kind described having, in combination, 80 means for assembling the articles in rows arranged side by side with the articles in each row arranged side by side, a device adapted to engage the endmost row to hold the several rows from advancing movement, means adapted to be operated by the operator for releasing said device from said endmost row to permit said row to advance independently of the other rows, and to cause 85 said device to engage the next succeeding row to hold the remaining rows from advancing movement, and upon release of said means by the operator acting automatically to release said device from said next succeeding row to permit the several rows to 90 advance, and to cause said device to re-engage said next succeeding row to limit the advancing movement of said rows, a stop for 95 limiting said advancing movement of the endmost row independently of the other rows, and means under the control of the operator for releasing said stop.

17. A machine for handling articles of the kind described having, in combination, 100 means for assembling the articles in rows with the articles in each row arranged edge to edge in upright position, raceways for receiving the several rows, respectively, each comprising a bottom strip upon which the articles rest in upright position, the several raceways and their bottom strips having 105 their upper portions spaced a distance apart to permit broken pieces of the articles to drop down between them, and their lower portions converging toward their lower ends so as to position said lower ends in close proximity, and means for vibrating said bottom strips.

In testimony whereof, I have signed my name to this specification this 8th day of December, 1925.

HARRY E. TOWNSEND.
